CLAIM

The ornamental design for an physiological pressure
monitoring instrument, substantially as shown and de-
scribed.

DESCRIPTION

FIG. 1 is a front perspective view of physiological
pressure monitoring instrument embodying our design;
FIG. 2 is a front elevational view thereof;
FIG. 3 is a left side elevational view thereof;
FIG. 4 is a right side elevational view thereof;
FIG. 5 is a back elevational view of the instrument case,
showing the side opposite that shown in FIG. 1;
FIG. 6 is a top plan view thereof.
FIG. 7 is a bottom plan view thereof.
